UNITED STATES PATENT OFFICE.

ALBERTO I. WOODRING, OF WATERLOO, IOWA, ASSIGNOR TO NATIONAL SAFETY DEVICES COMPANY, OF WATERLOO, IOWA.

WHISTLE-ACTUATING APPARATUS.

Application filed June 23, 1924. Serial No. 721,901.

To all whom it may concern:

Be it known that I, ALBERTO I. WOODRING, citizen of the United States, residing at Waterloo, in the county of Black Hawk and 5 State of Iowa, have invented certain new and useful Improvements in Whistle-Actuating Apparatus, of which the following is a specification.

My invention relates to improvements in 10 whistle actuating apparatus, and particularly to means for producing determined signals as in approaching a highway crossing, when the apparatus is mounted on a vehicle and constructed for operation by means 15 of a fluid under pressure.

This improvement is also related to the subject matter of my apparatus patented in 20 the United States on September 26, 1922, No. 1,430,273.

I have accomplished the said object by the means which are hereinafter described and 25 claimed, and which are illustrated in the accompanying drawings, in which Fig. 1 is a front elevation of my improved device for actuating whistles by means of fluid under pressure, with parts broken away. Fig. 2 is a vertical section of the operating valve therefor, with parts in elevation. Fig. 3 is a vertical section, on an enlarged scale, of 30 the starting motor and the delivering valve-chamber with adjacent structures as taken on the broken line 3—3 of Fig. 4, and Fig. 4 is a vertical section on the same scale of said parts taken at a right angle to Fig. 3 and 35 on the broken line 4—4 thereof.

This device is designed for use on a vehicle, such as an electrically or otherwise 40 propelled car on which is carried a supply of fluid under pressure such as compressed air, the latter being utilized in the actuation of the device and also in the actual sounding of a whistle or other audible signal on approaching a highway crossing.

The numeral 11 denotes a reservoir of 45 fluid under pressure having a pipe 55 in communication with the inlet-port 8 of a manually operable valve-device. This valve-device comprises a valve-chamber 2 made of 50 separably connected parts containing upper and lower chambers with the dividing septum provided with an apertured passage and valve-seat to receive the vaned stem 6 of a valve-head 7, the latter being positioned in the lower chamber. The inlet-port 8 communicates with the lower chamber, and an

oppositely located delivery-port 9 is in communication with the upper chamber, and a coiled spring in the lower chamber resiliently controls said valve to yieldingly close it and said passage. A plunger 5 is located 60 in the upper chamber and has an upwardly projecting stem 4, both centrally longitudinally bored with the upper end of the bore turned angularly to open sidewise at or near the tip of the stem. Upon the valve-chamber body is fixed a bracket member upon which is terminally pivoted at 3 an operating handle 1 having a cam edge to work against the rounded tip of the stem 4 to depress the latter.

A valve-chamber 41 and a starting motor cylinder 14 are made integral with a casting body adapted for fixed suspension on an overhead support. The middle part of said body has a spring barrel hollow 27. A rock-shaft 23 is centrally mounted in said spring barrel and in a bearing aperture in a bearing body 56 therein and has a terminal cranked part 30 within a dash-pot 29. A connecting-rod 31 connects said cranked part 30 to a plunger 32 pivoted to the lower end of the rod. Said plunger has a passage 33 contracted at its upper end to furnish a valve-seat for a ball check-valve 34. The dash-pot may contain oil the plunger working thereagainst to dampen the action of a coiled spring 28 which is positioned in the barrel 27 and connected between the hub 21' of a face-plate disk 21 and the inner wall of the spring-barrel. The disk 21 and its hub 90 are adjustably secured upon the shaft 23 for circumferential adjustment therearound by means of a removable dentated plate 24 secured on the disk and meshing with teeth of a rack-disk 22 secured upon the outer extremity of the shaft 23.

The cylinder 14 has heads 57 and 58, the latter apertured for the passage therethrough of the stem 17 of an imperforate packed plunger 15, and a spring 16 mounted on said stem damps the plunger in one direction. A connecting-rod 19 is pivotally connected at 18 to the projecting end of said stem and at 20 to the disk 21. The cylinder has an inlet-port 13 communicating with the conduits 12—10 which lead into the delivery-port 9 of the operating-valve body 2.

The cylindrical valve-chamber 41 has heads 59 and 62, both centrally apertured, the head 59 receiving an end of a pipe 53

which leads to the whistle 54. In the right-hand part of the valve-chamber 41 is inserted a section 46 having a port 49 in communication with the reservoir 11 by way of conduits 63 and 55. The section 46 has a hollow 50 whose left-hand end is closed by a screw-plug 60. The right-hand end of said section 46 has a hollow 44 communicating with a passage into said hollow 50, one end of said 10 passage having a valve-seat to which is fitted a valve-head 48 on a stem whose parts project oppositely therefrom, one through said passage and hollow 44 and the other through the hollow 50 surrounded by a coiled spring 15 61. A by-pass 45 leads from the hollow 44 through the section 46 into the hollow 51 of the valve-chamber. The right-hand cylinder-head 62 is centrally apertured and a reciprocable member 42 therein has a valve-seat to fit the rounded extremity of the 20 valve-stem 47.

Referring now to said Fig. 1, upon the end of a fixed bracket 35 is pivoted at its upper end a depending swinging arm 36. 25 Another swinging arm 38 has its outer extremity pivoted to the lower part of the arm 36 and limited in downward movement by a stop on the latter, and the free end of the arm 38 has a small roller 39 rotatably mounted thereon to lie in the path of movements to and fro of two spaced pairs of detents 25 and 26 on the margin of the rock-disk 21. The lowermost pair of detents 25 are the same circumferential breadth, while 35 the upper pair 26 are of smaller breadth with like intervals.

Operation: As it is required that a certain whistle signal be sounded before arrival at a highway crossing, the detents 25 and 26 are proportioned in breadths and in spacing to effect an intermittent sounding of the whistle 54 by the intermediate mechanisms above described as detailed in my said patent. When the operator depresses the handle 1 manually the cam edge thereof pushes downwardly the plunger-stem 4 to close the bore thereof and push down the valve-stem 6 and valve 7 to cut off communication between said bore and the upper 40 chamber, while opening the valve 7 against the spring below to effect communication between the ports 8 and 9, so that fluid under pressure may pass into the cylinder 14. The plunger 15 in said cylinder is thus pushed to the right so that by means of the connecting-rod 19 the disk 21 is rocked downwardly for a distance, so that the detents 25 and 26 in succession engage the roller 39 and swing the levers 38-36 to the 45 right, so that the finger 40 on the lever 36 pushes the member 42 to the left. This member pushes the valve-stem 47 to the left opening the valve 48 against the spring 60 61, so that fluid under pressure is allowed to pass through the communicating passages

to the chamber hollow 51 where it in turn enters the pipe 53 and operates the whistle 54. The signal is thus intermittently given as required with a regular and exact sequence and timing.

When the operating handle 1 is released, the reaction of the spring in the lower hollow of the chamber body 2 lifts and closes the valve 7, shutting off the communication between the ports 8 and 9. Residual fluid 70 under pressure in the upper hollow of the boy 2 and in the cylinder 14 then exhausts through the bore of the lifted valve-stem 4, as the plunger on the latter is first moved away from the stem 6 by air pressure from below. The spring 16 in the cylinder 14 reacts to return the plunger 15 and its stem 17 whereby the connecting-rod 19 rocks the disk 21 reversely, the roller and arm 38 75 swinging idly without moving the arm 36. As in this position of the arm 36 the finger 40 has released the member 42, the spring 61 in the chamber hollow 50 returns the valve 48 cutting off communication between the port 49 and the chamber hollow 51. The 80 latter has exhausted its fluid pressure by way of said whistle.

It is to be understood that various modifications may be made without departing from the scope of the invention, and that the apparatus may employ any desired fluid or flowing material, including steam or otherwise, and may be operated on any kind of device mounted for transportation, whether road or rail vehicles, cars, or otherwise.

Having thus described my invention, what I claim as new and desire to secure by Letters Patent, is:

1. An audible signaling device in communication with and operable by a source of fluid under pressure, a valvular device within and controlling said communication, and resiliently controlled mechanism of which certain elements are also within said communication and operatively associated with said valvular device to actuate it with a determined sequence of actuations of determined periods.

2. An audible signaling device in communication with and operable by a source of fluid under pressure, a valvular device controlling said communication, mechanism of which certain elements are also within said communication and operatively associated with said valvular device to actuate it with a determined sequence of actuations of determined periods, and a resiliently controlled starting motor for said mechanism.

3. An audible signaling device in communication with and operable by a source of fluid under pressure, a valvular device controlling said communication, mechanism of which certain elements are also within said communication and operatively associated

- with said valvular device to actuate it with a determined sequence of actuations of determined periods, a resiliently controlled starting motor in independent communication with said source of fluid under pressure, and a manually operable resiliently controlled valvular device controlling the last-mentioned communication for an initial actuation of said starting motor.
- 10 4. An audible signaling device in communication with and operable by a source of fluid under pressure, a valvular device within and controlling said communication, mechanism partly within said communication operatively associated with said valvular device to actuate it with a determined sequence of actuations of determined periods, a resiliently controlled starting motor in independent communication with said source of fluid under pressure, and a manually operable resiliently controlled valvular device, controlling the last-mentioned communication for an initial actuation of said
- 5 starting motor, said operative mechanism including resiliently controlled means for 25 resetting the same after operation.
5. In combination, a source of fluid under pressure, a whistle signaling device operable only by fluid pressure, and communicating with said source mechanism for intermittently actuating said device including a fluid operated starting motor resiliently controlled, a valvular device within said communication and actuated by said starting motor intermittently to admit fluid under pressure to said signaling device, said valvular device including resilient means also within said communication for resetting it after operation, and a manually actuated valvular device in operative association with 30 35 40 said starting motor containing means for resetting it after actuation, automatically.

Waterloo, Iowa, June 6, 1924.
In testimony whereof I affix my signature.

ALBERTO I. WOODRING.
